US00D966502S

(12) **United States Design Patent** (10) Patent No.: **US D966,502 S**
Muldowney (45) Date of Patent: ** *Oct. 11, 2022

(54) **ABSORBENT PAD**(71) Applicant: **Hemispheres for All, LLC**, Byron, IL (US)(72) Inventor: **Thomas A. Muldowney**, Byron, IL (US)(73) Assignee: **Hemispheres for All, LLC**, Byron, IL (US)

(*) Notice: This patent is subject to a terminal disclaimer.

(**) Term: **15 Years**(21) Appl. No.: **29/805,024**(22) Filed: **Aug. 24, 2021****Related U.S. Application Data**

(60) Continuation-in-part of application No. 29/770,822, filed on Feb. 17, 2021, now Pat. No. Des. 930,155, which is a division of application No. 29/710,453, filed on Oct. 23, 2019, now Pat. No. Des. 914,205, which is a continuation-in-part of application No. 14/970,831, filed on Dec. 16, 2015, now abandoned.

(57) **CLAIM**

The ornamental design of an absorbent pad, as shown and described.

DESCRIPTION

FIG. 1 is a top perspective view of an absorbent showing my new design.

FIG. 2 is a bottom perspective view of the absorbent pad of FIG. 1.

FIG. 3 is a front view of the absorbent pad of FIG. 1. The rear view of the absorbent pad of FIG. 1 is identical to that shown in FIG. 3.

FIG. 4 is a top view of the absorbent pad of FIG. 1.

FIG. 5 is a right side view of the absorbent pad of FIG. 1. The left side view of the absorbent pad of FIG. 1 is identical to that shown in FIG. 5; and,

FIG. 6 is a bottom view of the absorbent pad of FIG. 1.
